UNITED STATES PATENT OFFICE.

JAMES DUVALL AND GLEN W. SMITH, OF CAMAS, WASHINGTON.

BAG-BUNDLING MACHINE.

Application filed October 13, 1925. Serial No. 62,246.

Our invention relates to machines for wrapping bundles, for instance, paper bags, in which the lateral ends of the sheet of wrapping paper are folded about said package and pasted together. Bundles of paper bags to be wrapped are arranged in bunches containing approximately one hundred bags in each and six of said bunches are stacked one upon the other. The common manner of 5 wrapping said bundles heretofore was to fold the lateral ends of the sheet of wrapping paper about said bundle and then to tie said bundle with a length of string. Bundles tied in this manner, however, are not only rather 10 bumpy but also tend to be compressed unevenly throughout their length so as not to be 15 of uniform height.

The object of our invention is to provide an improved, simple and efficient machine by 20 which bags stacked in the form of a bundle containing an equal number of units, may be successively placed on sheets of wrapping paper or other similar serviceable material and continuously moved through the machine 25 on said sheets, the machine operating to apply paste to one end of the wrapping sheet and then lapping the lateral ends about said bundle and causing said pasted portion to set by the application of heat. The bundles are 30 compressed before being wrapped and said compression is maintained during the pasting operation and continues until after the ends 35 of the wrapping sheet are firmly pasted together so as to prevent the wrapping sheet from being subjected to any strain which would tend to displace its overlapped ends. By passing bundles of bags through a machine of this character successively, bundles 40 of uniform height are produced and because the ends of the wrapping sheet are pasted along their entire length, the bundles are 45 maintained in an equally compressed condition and thus said bundles are regular in outline and pack very compactly when shipped.

A further object of our invention is to arrange our improved machine so that it can be readily adjusted to wrap bundles of different sized bags. All of the relatively 50 adjustable devices in our machine are connected together so that the adjusting of one part thereof will cause a corresponding adjustment of the other adjustable portions. That is, although the various adjustable portions 55 of our machine are located some distance from each other, they are connected by members

arranged so that one of said adjustable portions is moved to accommodate one size bag to be wrapped, said adjustment will correspondingly move the other portion accordingly. 60

A further object of our invention is to provide an automatic wrapping machine of this character in which the bundles of bags and the sheets of wrapping paper are fed continuously upon a longitudinally arranged carrier or conveyor, which extends the full length of the wrapping machine and thus said bundles and said wrapping sheets are carried by a single carrier or conveyor, and thus the tendency of said bundles or sheets to 65 be displaced is minimized. 70

A further object of our invention is to provide shearing devices which are adapted to divide a continuous strip of wrapping material into sheets of the correct length, said 75 sheets being connected by easily broken portions of said strip. Said portions serve to maintain the sheets in their correct relationship to each other, but permit them to be easily broken when the wrapped packages are 80 discharged from the machine. Said connecting portions of the wrapping sheet are arranged so that they always will lie adjacent to the carrier or conveyor and thus said sheets 85 may be left connected until the packages 90 are discharged, fully wrapped. The shearing devices are also synchronized relatively to the speed of the conveyor for the bundles and thus the length of said sheets of wrapping paper can be varied by changing the 95 relative timing of said shearing devices.

A further object of our invention is to provide guides or positioning devices for the bundles to be wrapped so that said bundles not only will be correctly positioned upon 100 said conveyor but also will be arranged upon the sheet of wrapping material so that the previously formed folds will extend along the adjacent edges of the bundle to be wrapped. One of said guide elements preferably consists of a movable belt synchronized relatively to the conveyor and inclined towards the other of said guides so that said movable guide belt will co-operate with said conveyor to feed said bundle through said 105 machine for a short distance.

A further object of our invention is to provide compressing mechanism for the bundle which co-operates with the conveying mechanism and is arranged so as not to interrupt 110

the movement of said bundle through the machine. Said compressing mechanism is arranged to make an oblique angle with the plane of said conveyor or carrier, and the discharge end of said compressing devices are arranged so that the space between said end and said conveyor is less than the normal height of said bundle to be wrapped and thus said bundle is compressed into a smaller bundle than it normally assumes while it is being wrapped. Said compressing action thus relieves the wrapping sheet of any strain and thus the pasted ends of said sheet will not tend to be displaced while the paste is drying, and when the pressure is released, upon the bundle being discharged from said machine, the resultant expansion will tend to tension the wrapping sheet and produce a relatively solid bundle.

20 A further object of our invention is to provide folding mechanism for wrapping the lateral ends of said wrapping sheet about the bundle, said folding mechanism serving first to lift the flat sheet of wrapping paper upon which the bundle is carried to parallel vertical positions relatively to the horizontal conveyor so as to extend upwardly along the sides of the bundle. Successive folding devices then fold the ends of said upstanding portions inwardly, one over the other, so as to cause them to be overlapped and thus bring the pasted end over the other of said lateral ends. Said folding mechanism comprises a bridge-like portion arranged directly above the bundle. Said latter inturned fold is made over said bridge-like portion, said bridge-like portion tending to compress the bundle against the conveyor and the wrapper thus is left relatively free, that is, independent of the compression of the bundle. Thus, during the time that said inturned overlapped fold is made the sheet of wrapping material is subjected to no tension by the compression of the bundle and thus the overlapped ends do not tend to be pulled apart.

To this end our invention comprises the certain mechanism and combinations of devices hereinafter fully described with reference to the accompanying drawings. In the latter:

Fig. 1, Sheet 1, is a diagrammatic view of the belt-like conveyor, the sheet of wrapping material and a number of bundles of bags being wrapped, said view diagrammatically showing the progressive operations of wrapping said bundles as they are passed by said belt-like conveyor through our machine;

Figs. 1^a and 1^b, Sheet 1, are larger scaled diagrammatic views showing a sheet of wrapping paper, the package to be wrapped therein and the creases for marking the location of the folds to be made in said sheet of wrapping material; said figures diagrammatically illustrate the manner in which the creasing rolls are adjusted to accommodate

different sized packages of bundles of bags;

Fig. 1^c, Sheet 1, is a fragmentary diagrammatic view of a portion of the belt-like conveyor and a sheet of wrapping material with a bag bundle carried thereon, said figure is 76 diagrammatic, showing the set of folding devices adapted to form the inturned fold about said package over the bridge-like portion, a portion of said bridge-like portion also being shown;

Figs. 2, Sheet 2, and 2^a, Sheet 3, are complementary and represent a plan view of our machine;

Figs. 2^b, Sheet 2, and 2^c, Sheet 3, are also complementary and are diagrammatic representations of the operations of our improved machine, as shown in Figs. 2 and 2^a, the diagrammatic representation of a particular operation being in vertical alinement with the portions of the machine shown in 85 Figs. 2 and 2^a which perform said operation;

Figs. 3, Sheet 4, and 3^a, Sheet 5, are also complementary and represent a side elevation of our machine on a slightly larger scale than 90 the plan view, portions of the machine being shown as broken away in these figures to disclose details of construction; and the compressing elements which comprise the after end of our machine, are shown as foreshortened;

Figs. 4, Sheet 6, 4^a, Sheet 7, 4^b, Sheet 8, and 4^c, Sheet 9, are also complementary views taken on a still larger scale representing a longitudinal section through our machine, 100 said figures also show bundles and sheets of wrapping material;

Fig. 5, Sheet 6, is an end elevation of our improved machine taken in direction of the arrow 5 in Fig. 4;

Fig. 6, Sheet 6, is a fragmentary perspective view of one of said creaser elements and a portion of the adjusting devices therefor;

Fig. 7, Sheet 7, is a fragmentary perspective view of the pivoted supporting arm which 110 carries one portion of the upper compression belt elements;

Fig. 8, Sheet 9, is an end elevation of our improved machine taken in the direction of the arrow 8 in Fig. 4^c;

Fig. 9, Sheet 10, is a transverse section through our machine taken on the line 9—9 of Fig. 4^b;

Fig. 10, Sheet 10, is a transverse section through our machine taken substantially on 120 the line 10—10 of Fig. 4^a;

Fig. 11, Sheet 11, is a diagrammatic fragmentary view of the connections between the relatively adjustable operative devices, said connections being adapted to maintain the 125 relative positions of said operating devices constant so that an adjustment of one operative device will cause a corresponding adjustment of the others; and

tive view of the upper compressing element and the bridge-like portion which forms a continuation thereof, over which the inturned fold of the wrapping sheet is made.

- 5 In order to facilitate the understanding of our machine, we will describe the construction and operation of our machine in connection with the successive functions of the various parts as they occur during the operation of 10 wrapping bundles of bags.

Our improved bag bundling machine comprises a frame 1 upon which all of the operating mechanism is carried. A sheet *b* of wrapping material, preferably paper, is 15 passed on to the bed 1^a of said frame 1, from the left as viewed in Figs. 1, 1^a, 2, 2^a, 3, 3^a, 4, 4^a, 4^b and 4^c. Said supply of paper is carried by a parent roll *b'* and passes over a guide roll *b''* on to the initial end of the machine. Said 20 parent roll of paper *b'* is preferably mounted on a rotatable mandrel carried upon the initial end of the machine, said mandrel, however, not being shown in the drawings because usually a printing or labeling device 25 is interposed upon the initial end of the machine as shown, and between the parent roll and the creasers. Said printing or labeling mechanism forms no part of our invention and therefore is eliminated from the drawings.

Adjustable creasing devices.

In passing onto the bed our machine the sheet of wrapping material *b* moves as a 35 continuous strip and passes under a plurality of relatively adjustable creasing rolls 3^a, 3^{a'}, 3^b and 3^{b'}, Figs. 2, 4, 5 and 6.

The creaser rolls 3^a, 3^b, 3^{a'} and 3^{b'} are 40 rotatably mounted in arms 3^x, 3^y, 3^{x'} and 3^{y'} which are fixed to the channel like members 3^x, 3^{x'}, 3^y and 3^{y'}, which are movable on a transverse bar 3 and through which parallel transverse bars 4^a, 4^b and 4^{b'} are passed.

The said creaser rolls normally bear against 45 a roller 3^c, mounted transversely of the machine and the continuous sheet of wrapping paper passes between the creaser rolls and the under roller 3^c, whereby longitudinal continuous creases are formed in the wrapping paper.

The channel-like members 3^x, 3^{x'}, 3^y and 3^{y'} are relatively adjustable on the rods 4^a, 4^b and 4^{b'} to provide for the proper spacing of the creases to conform with the folds about various sizes of bag bundles which our machine 55 is adapted to operate on.

The channel-like member 3^y is fixed to the bar 3 as the position of the crease so formed is constant, the other creasers being 60 adjustably spaced relatively therefrom on the rods 4^a, 4^b, 4^{b'}, which are longitudinally movable in the member 3^y.

The members 3^x, 3^{x'}, and 3^y are fixed by any suitable means, such as a set screw, to the rods 65 4^a, 4^b, and 4^{b'}, respectively, and the rods

themselves are longitudinally movable and are connected at each end to flexible cables 5^a, 5^b, and 5^{b'}, respectively.

The cables 5^a and 5^b connected to the right hand ends of the rods 4^a and 4^b pass 70 over pulleys *f* and *f'* and are provided on their ends with counter-weights 6^a and 6^b and the cables 5^{a'} and 5^{b'} connected to the other ends of said rods 4^{a'} and 4^{b'} pass over pulleys *g* and downwardly and under pulleys 75 8^b and 8^a, fixed to the floor beneath the machine, and thence upwardly over two pulleys 8 fixed to the frame 1, and then around the pulleys 101 and 101^a respectively. The cable 5^a is fixed to the opposite side of the frame 1. The cable 5^{b'} passes upwardly under a pulley 8^c fixed on the frame 1 and to the frame section which carries the upper conveyor belt and supporting mechanism which constitutes also the upper compress- 85 ing member.

The cables 5^a and 5^b then are passed around horizontal companion pulleys 101 mounted on the lower end of an upright shaft 94 of the guiding mechanism, hereinafter described, and the cable 5^{a'} is then fixed to the frame 1 of the machine.

The cable 5^{b'} is passed under a pulley 8^c fixed to the frame section 1 and upwardly to the upper frame section 7 and fastened 95 thereto.

The cable 5^b connected to the left hand end of the rod 4^b passes over one of the loose companion pulleys *g* and to a counter-weight 6^b 100 connected on its end.

The cable 5^b connected to the right hand end of the rod 4^b passes over another of the companion pulleys *f* and downwardly and under a pulley 5^c fixed to the floor beneath the machine and then under a pulley 5^d also 105 fixed to the floor and upwardly to the frame section 7, to which it is fastened.

Thus by this construction, as the upper frame section 7 which is vertically adjustable to the bed of the machine is raised or lowered, the creaser rolls 3^a, 3^b and 3^{b'} will be moved along the support 3 and the creases so formed will be spaced properly to conform to the folds along the top and bottom edges 110 of the bag bundles.

A flexible cable 9^a is fixed to any convenient point on the pasting device, herein-after described, and leads transversely of the machine over a pulley 9^b and downwardly and under a pulley 9^c and under a pulley 9^d 120 and upwardly and over a pulley 9^e fixed on the frame section 7, and is then connected to an arm 9^e which is pivotally connected at its ends respectively to the cross member 97^c and to an arm 9^h, pivotally connected to the 125 cross member 94^c so that the pasting device will be moved laterally one-half the distance of the movement of the cross member 94^c.

Thus the pasting device is adjustably moved laterally with the movement of the 130

frame section 7 and in unison with the adjustable creasing means above described. Thus to apply a narrow strip of paste to the continuous strip of wrapping paper, 5 properly positioned relatively to the creases and the size of the bag bundle being wrapped.

Wrapper cutting devices.

The sheet of wrapping material after passing 10 under the creasers passes between two pairs of driven, transverse drawing rolls 10-10^a and 11-11^a which are spaced apart and in said space a plate 12 is arranged, provided with a narrow longitudinal aperture 15 12^a therein through which the sheet of wrapping material *b* passes and said aperture is only slightly wider than the thickness of the wrapping material *b*. As shown in Fig. 4, a guide 12^b is arranged on the lower edge of 20 the aperture 12^a and the rearward upper edge of the aperture 12^a is rounded as at 12^c.

A transverse cut-off knife 13 is mounted on arms 13^c, which are pivoted at their ends on a transverse rod 14. The cut-off knife 13 is 25 provided with serrated edges 13^b and with spaced notches 13^a, which are relatively narrow and of sufficient depth so that the portion of the wrapping material adjacent these notches will be uncut, and thus the section of 30 the wrapping material so cut will remain connected, but easily separated.

The cut-off knife 13 is provided with a longitudinal shoulder 13^a which normally bears against a transversely arranged stop rod 15 35 by the action of compression springs 16 which are mounted over rods 16^a, which are hinged to the arms 13^c as at 16^c and at their lower ends 16^b they are pivotally mounted on a rod 11^b fixed to the frame 1. The rods 40 16^a are extensible and the springs 16 thus normally hold the knife 13 against the stop rod 15. The portion of said wrapping sheet thus intersected, is held taut by the sets of drawing rolls 10, 10^a, and 11, 11^a and thus 45 when said blade passes through said sheet, the severance of said sheet is aided by the tautness of the wrapping sheet.

It is desirable that the severed sheets of 50 wrapping material be connected because said connecting portions tend to hold the sheets in correct relative position to prevent them being displaced from the conveyor. The connecting portions *b*^a, in said sheet between the severed sections are arranged closely to 55 the two middle folds, as shown in Fig. 1, and thus said connected portions do not interfere with the folding of said sheets around the bundle. When said bundle is discharged from the end of the machine, said portion can 60 be easily broken by the attendant so as to permit the separate, wrapped bundles to be stacked one on top of the other.

A rotating spiral cam 17 is arranged so that the outstanding flange 17^a thereon per-

iodically engages on its inner face a roller 65 13^c carried by one of the arms 13^c of the cut-off knife 13, and said spiral cam in rotating moves the knife 13 downwardly so that the shoulder 13^a is moved away from the stop rod 15. In moving the arms 13^c of the cut-off 70 knife 13, the cam 17 compresses the spring 16 still further and thus when said roller 13^c passes off the end 17^b of the cam, said knife 13 is driven upwardly by the compression spring with great velocity, and is driven 75 through the sheet of wrapping material *b* thus severing the same which is securely held against the operation of the blade 13 by the plate 12 and the rollers 10 and 10^a, and 11 and 11^a. Said spiral cam 17 is carried by a 80 rotatable driven shaft 18 which extends transversely of the frame of the machine and extends into a casing 18^a which encloses a speed change device 25, the driving gears in said speed change device being connected to 85 the driving mechanism of the machine.

Any suitable speed changing device may be used and therefore will not be described in detail. By changing the speed of rotation of said shaft 18 the timing of the cutting intervals of said cut-off knife will correspondingly be changed and, inasmuch as the sheet of wrapping material passes continuously over the bed of the frame 1, the length of the wrapping material between the cuts will 95 thus be controlled correspondingly. Experience has proven that when our machine is used for wrapping paper bags the different sized bags require wrapping sheets which vary in lengths from 8" to 15" and thus we 100 provide a speed change device which has eight adjustments so that the timing of the knife can be regulated so as to cut sheets of wrapping material accordingly, each adjustment producing but 1" difference in length 105 of wrapper.

Bundle positioning devices.

After said strip of material has been cut into sheets, said sheets are fed along the bed 110 of the machine by the pair of drawing rolls 11-11^a and are fed onto the main conveying belt 19 which extends from this point entirely through the machine. The sheet of wrapping paper *b* passes partially under a 115 plate 20 which is spaced from the bed of the machine and which terminates at a point adjacent the edge of the conveying belt. We provide a longitudinally arranged vertical partition 21 which lies along the other side 120 of said belt and thus the edge 20^a of said plate and said vertical partition 21 forms a groove in which the bundles to be wrapped may be placed, said groove being in longitudinal alinement with said belt.

An operator who stands beside the machine places the bundles on the plate 20 and pushes them onto the continuous wrapper 125

which is being carried along by the belt 19, and against the partition 21. The partition 21 serves to arrange said bundles in correct vertical alinement with the sheet and inasmuch as the transversely cut edges of the sheets of wrapping material are only spaced apart the width of the bundle to be wrapped. The rear end of the preceding bundle serves as a stop against which the forward end of the bundle being centered can be positioned. That is, the bags which are centered transversely of the machine by the vertical partition 21 can be positioned longitudinally thereof also if the first package is correctly located relatively to the cut edges of the wrapper merely by arranging said packages so that they abut one against the other in passing along the machine.

We provide an adjustable arm 22 which is pivotally supported diagonally over the bed of the frame upon bearings which support the driven shaft 23. The adjustable arm 22 carries a pivoted T-shaped head 24 upon its free end, and is pivotally mounted upon the pin 25 and carries pulleys 26 and 26^a upon its extremities. Said vertical shaft 23 also carries a pulley 26^b which is arranged in horizontal alinement with said pulleys 26 and 26^a, and a belt 27 is mounted about said pulleys 26, 26^a and 26^b, and is driven by the rotation of the pulley 26^b. The lineal speed of said belt is exactly the same as the speed of the main conveying belt 19 so that said belt 27 also acts as an auxiliary conveying device for the bag bundles 2. Said arm 22 is adjusted to its correct position by a handle 28 which is provided with locking devices and the head is also arranged so that the belt 27, in passing around the pulleys 26 and 26^a, makes a more or less oblique angle thus bringing the bundles into alinement with the face of the vertical partition 21. The pulley 26^b is arranged so that the spacing between the belt, in passing thereover, and the face of the vertical partition 21 corresponds exactly to the width of the bundle being wrapped. Said belt 27 thus is not only a guide for but also tends to straighten up the bundle by compressing the bags or other elements in the bundle against the face of the vertical partition 21. Said belt 27 and the vertical partition 21 are of such widths as to be capable of guiding and alining the tallest bundles and thus when said bundles 2 pass beyond said device they are not only in vertical alinement with the sheet of wrapping paper, but are also straightened and in condition for being wrapped. Longitudinally arranged wires 29 are provided on the right hand side, looking forward, of the bed of the machine to hold down the several sheets of wrapping material b so that they will not be displaced relatively to the conveyor belt 19 by the placing of said bundles in position, said wires extending along the bed of said machine to a

point at which the compressing devices act upon the bundles.

Pasting mechanism.

The paster roll 9 is also arranged at the right hand side of the machine, looking forward, and applies a strip of paste b⁴ to one of the edges of the wrapping sheets. Paste is supplied to the paster roll 9 by a roller 30 which bears on another roller 30^b, so arranged in a paste container 30^a that it is only partially immersed therein. The paster roll 9 is carried by a sliding bracket 31 mounted upon laterally extending supporting rods 31^a which permit the paster roll to be adjusted laterally. As before mentioned, said bracket is drawn laterally along said rods 31^a by the cable 9^a so that the position of the strip of paste b⁴ applied to said sheet b, may be adjusted relatively to the position of the creasing and forming devices.

Compressing and folding devices.

The section of wrapping paper b at this point, is still flat and the bundles 2 of bags are carried upon the middle of the sheet of wrapping paper, the bundles being moved along by the belt 19. The bundles next move under a series of belts 32, 32^a and 32^b which are inclined towards the belt 19 in the direction of travel of the belt 19.

The belts 32, 32^a and 32^b are mounted over pulleys 33, 33^a and 33^b and over a common pulley 39. The pulleys 33, 33^a and 33^b are mounted on an arm 37 hinged on a shaft 38 on which the pulley 39 is keyed, and the said shaft 38 is journaled in the movable frame section 7, hereinafter described.

Referring to Fig. 7, the supports 34, 35 and 36 respectively of the pulleys 33, 33^a and 33^b are adjustably fastened in shackles 37^a and are adjustable by means of set screws 34^a, 35^a and 36^a, bearing against the ends of the said support.

The pulley 33^a is of somewhat larger diameter than its companion pulleys, but is mounted on a pin 35^b mounted between the sides of the supports 35. The pulleys 33 and 33^b are similarly mounted in supports 34 and 36, but at a lower level than the pulley 33^a, and by this arrangement the peripheries of the three pulleys are in a common plane tangential with the pulley 39.

By this construction, the pulleys 33, 33^a and 33^b are mounted closely together, and at the same time individual adjustments of each of the belts 32, 32^a and 32^b is provided.

The arm 37 is adjustable relatively to the upper frame section 7 hereinafter described by means of an elevating screw 43 and a hand wheel 42, which bears against the top of the arm 37, by which it is raised or lowered by rotating the hand wheel 42.

A bridge member 44, Fig. 12, is fixed to the arm 37 by downwardly extending supports

44^a, which hold the belts 32, 32^a and 32^b evenly against the bag bundles, and said bridge 44 is provided with three grooves 44^b adapted to receive the belts 32, 32^a, 32^b and in which 5 rollers 45 are mounted and which the belts bear against as they move.

By providing a number of narrow belts in the place of one wide belt, we eliminate the tendency of the top bag of a bundle of sticking to the belt, and thus becoming torn against 10 the rearward edge of the bridge member 44.

Just before the bundles are carried under the belts 32, 32^a and 32^b, we provide upright parallel curved wires 47 and 47^a. The wire 15 or guide 47 is fixed to a plate bolted to the supports for the belt 19 hereinafter more fully described, and the wire 47^a is fixed to a plate bolted to a member 47^a on the other side of the belt, which is mounted for lateral movement 20 on transverse screws 89^a and 90^a hereinafter described.

Thus lateral adjustment is provided for the curved wires 47 and 47^a whereby the ends of 25 the wrapper of any size bundle may be lifted and folded along the two center creases on each side of the bag bundle.

After the bag bundles are carried under the belts 32, 32^a, and 32^b and compressed, they 30 pass under a bridge section 56 which is supported from the frame section 7 in a horizontal plane tangential with the pulley 39 so that the bag bundles are held compressed thereunder. The adjacent ends of the bridge member 44 and the bridge section 56 are connected 35 (Fig. 12) by a thin flexible member 44^c provided with extensions of the grooves 44^b in which the belts 32, 32^a and 32^b move and provides a limited angular movement between them to allow for the relative adjustment 40 of the one to the other.

The bridge section 56 is provided with a forwardly extending plate 50 bolted thereto, which is tapered at its other end as at 50^a. The plate 50 is exchangeable for others of 45 different widths, to conform to the width of the bundle being wrapped.

Adjacent the point of the bag bundles are carried, under compression, under the plate 50, are provided two folding plates 94^b and 49, 50 on the right and left sides of the belt 19 respectively, the latter folding plate being arranged in advance of the former.

The folding plate 94^b is suspended from a 55 longitudinal member 94^c which is slidably mounted for lateral movement on a transverse horizontal bar 98 supported from the frame section 7, at each end by angles 98^b, and for vertical movement with the said frame section 60 on parallel upright shafts 94, so that the folding plate 94^b is adapted for both vertical and lateral adjustment relative to the width and height of the bundle by means hereinafter described.

The folding plate 49 on the right hand side 65 is suspended from a parallel horizontal mem-

ber 97^a, also, mounted on the vertical bar 98 which is adapted for vertical movement with the frame section 7 but is held in fixed alignment with the wall 21.

The folding plates 94^b and 49 are so arranged relatively to the plate 50, that as the bundles are carried under the said plate on the belt 19, with the sides of the wrapping sheet projecting upwardly above each side of the bundle, the plate 94^b on the left hand side, first folds the adjacent side of the sheet down over the plate 50 and the folding plate 49 then folds and presses the right hand side of the wrapping sheet, which has already had paste applied, as before described, down on the former.

By this construction and arrangement the wrappers are loosely folded and pasted around the bag bundles which are now under compression, so that when the bundles are released from the said compression, at the end of the machine, the wrappers will hold the bundle securely and compactly.

The bridge section 56 extends from the pulley 39 to a pulley 54 upon which an endless belt 55 is mounted and the bag bundles pass out from under the folding plate 94^b and the folding plate 49 and under the endless belt 55.

The endless belt 55 is mounted over rollers 54 and 61 which are mounted on the upper frame section 7 and the portion of the belt which bears on the bag bundles is held evenly along its entire surface against the bag bundles by rollers 57, mounted on a bridge 57^a, which is fastened to the frame section 7 by downwardly extending supports 57^b.

The belt 55 serves to hold the bag bundles compressed and to press the pasted portion of the wrapper down on the other end of the folded wrapper.

An electric heating element 59 is provided above and adjacent the belt 55 and arranged so as to heat the pasted seam of the wrapper and thus hasten the drying of the pasted seam, in order that the bag bundle when discharged from the machine will not break open.

The bag bundles are then carried continuously between the belts 19 and 55 to the end of the machine when they are discharged onto any suitable platform and the bag bundles, when released from the compression of the said belts expand and tighten the wrapper so that a solid and firm bundle is ready for distribution.

The upper frame section 7 is supported by four threaded screws 58 arranged in pairs at each side of the machine. Said screws are rotatably mounted in the frame 1 and engage threaded bushings 58^a carried by the upper frame section. All of said screws are connected by an endless chain 60 which passes about sprockets 60^a, mounted on the lower ends of the said screws. One of said screws is provided with a hole 58^b adapted to receive a turning tool 58^c and thus by rotating said 13

screw all of said screws will be turned in unison so as to lift the frame 7 uniformly at each of its four corners.

The pulley 61 is mounted on a transverse shaft 62^b which is supported on each end in journals 62^a in which screws 62 are rotatably mounted. The screws are threaded into bosses 63 fastened to the upper frame section 7. By this construction the tension of 10 the belt 55 may be adjusted by rotating the screw 62.

We preferably provide two vertically arranged belts 64 at each side of the belt 19 at a point between the pulleys 39 and 54 at 15 which point the lateral ends of the sheets of wrapping paper are being enfolded about the bundles of bags. Said belts are also driven at exactly the same lineal speed as the belt 19.

20 As is shown in Fig. 9, the driven vertically arranged belts 64 may be moved towards and from each other to accommodate bundles of bags of different widths. This adjustment is provided by four threaded screws 89, 89^a, 25 90 and 90^a, which extend transversely of the machine and engage threaded nut-like portions 93 on the vertical shafts 94 on which the cross member 94^c is also journaled. Said screw 89 is provided with an adjusting handle 91 by which said screw can be rotated. Said screws 89, 89^a, 90 and 90^a are provided with sprockets 89^b, 89^c, 90^b and 90^c, respectively, which are connected by a chain 96. Thus when the screw 89 is turned by the handle 91 35 all of said screws are turned simultaneously so that the said vertical shafts 94 are moved either towards or from the similar fixed vertical supports 97, as shown in this figure. Said vertical shafts 94 and supports 97 are 40 slidably held at their upper ends by transverse shafts 98.

One of said vertical shafts 94 carries directly the relatively movable pulleys 100 and 101 previously referred to about which 45 the cables 5^a and 5^b, respectively, are mounted.

Power is provided for the machine through a shaft 65. Outboard pulleys 66 and 67 are provided on said shaft, one being a loose pulley and the other a tight pulley. Said shaft 65 is connected to a shaft 68 by intermeshing gears 69 and 70 carried by said shafts 65 and 68, respectively. Power is transmitted from shaft 68 to shaft 71 by gears 72 and 73 on said shaft 68 and 71, respectively. Said shaft 71 carries pulley 74 about which the belt 19 passes. Power is transmitted through a chain 75 to the shaft 18 which drives the cut-off knife, which is mounted 55 about a sprocket 76 fastened over the shaft 65 and to the driven gear in the speed change device for the cut-off knife as shown in Fig. 2.

The driven pulley 54 about which the belt 65 55 is mounted is driven by a chain 77 which

passes over a sprocket fixed to the shaft 65 and over a sprocket fastened to the shaft 78 on which said pulley 54 is fixed. A sprocket 80 is also fixed to the shaft 78 of the pulley 54 and a chain 40 is mounted over said sprocket 80 70 and over a sprocket 41 on the shaft 38, on which the pulley 39 also is fixed. Said chain 40 thus drives said pulley 39 and therewith the belts 32, 32^a and 32^b mounted thereover.

(See Fig. 3.) A chain 84 is mounted over a driven sprocket 85 and a sprocket 86 which is fixed to the shaft 87 on which the pulley 88 for the belt 19 is mounted and said chain 84 also drives the rolls 10 and 10^a, 11 and 11^a, 80 which are connected thereto by gears 10^b and 10^c, 11^b and 11^c, respectively. All of the said rolls are driven to feed the sheet of wrapping paper 7 therethrough.

We claim:

1. In a bundle wrapping machine, in combination with a traveling carrier adapted to carry a wrapping sheet supporting a bundle, adjustable means for forming relatively spaced folding creases in said wrapping sheet, correspondingly adjustable means for folding the lateral ends of said sheet along said creases about the sides and the top of the bundle carried by said carrier, and means connected to said creasing means and said folding means operable to position them simultaneously relatively to the cross section of the bundle to be wrapped.

2. In a bundle wrapping machine, in combination with a traveling carrier adapted to carry a wrapping sheet supporting a bundle, and adjustable means for forming relatively spaced folding creases in said wrapping sheet, correspondingly adjustable means for folding the lateral ends of said sheet along said creases about the sides and the top of the bundle carried by said carrier and means for applying adhesive to the extremity of one of the overlapped ends of the wrapping sheet, and means connected to said creaser means, said folding means, and said adhesive-applying means operable to position these devices simultaneously relatively to the cross section of the bundle to be wrapped.

3. In a bundle wrapping machine, a traveling carrier adapted to carry a wrapping sheet supporting a bundle, a fixed alining element located on one side of said carrier, a companion alining element located on the opposite side of the carrier, and operating to engage and move the bundle against said fixed alining element.

4. In a bundle wrapping machine, a traveling carrier adapted to carry a wrapping sheet supporting a bundle, a fixed alining element located on one side of said carrier, an adjustable companion alining element located on the opposite side of the carrier, and operating to engage and move the bundle against said fixed alining element.

5. In a bundle wrapping machine, a travel-

5 sides of the bundle, and then folding the extremities of said ends one over the other over said bridge section, and a traveling belt located at the far end of said carrier, above and parallel with the latter, adapted to bear on the top of the bundle carried by the carrier as received from under said bridge section, co-operating with said carrier in effecting the further movement of the bundle through the 10 machine, and holding the bundle in its said compressed state during such further movement.

13. In a bundle wrapping machine, a traveling carrier adapted to carry a wrapping sheet supporting a bundle, a fixed alining element located on one side of said carrier, a companion alining element located on the opposite side of the carrier, and operating to engage and move the bundle against said fixed alining element, a bridge section located in the middle of the machine, above and parallel with said carrier, and spaced from the latter relatively to a predetermined height of the bundle carried thereby, means for compressing the bundle carried by said carrier to the height permitting the bundle to pass under said bridge section, means in co-operation with said carrier functioning first to lift the lateral ends of the wrapping sheet against the 25 sides of the bundle, and then folding the extremities of said ends one over the other over said bridge section, means co-operating with said carrier and located adjacent to and forward of said bridge section, adapted to restrain said bundle compressed as received, and while moved from said bridge section.

14. In a bundle wrapping machine, a traveling carrier adapted to carry a wrapping sheet supporting a bundle, a fixed alining element located on one side of said carrier, a companion alining element located on the opposite side of the carrier, and operating to engage and move the bundle against said fixed alining element, a bridge section located in the middle of the machine, above and parallel with said carrier, and spaced from the latter relatively to a predetermined height of the bundle carried thereby, means for compressing the bundle carried by said carrier to the height permitting the bundle to pass under said bridge section, means in co-operation with said carrier functioning first to lift the lateral ends of the wrapping sheet against the sides of the bundle, and then folding the extremities of said ends one over the other over said bridge section, and a traveling belt located at the far end of said carrier, above and parallel with the latter, adapted to bear on the top of the bundle carried by the carrier as received from under said bridge section, co-operating with said carrier in effecting the further movement of the bundle through the machine, and holding the bundle in its said compressed state during such further movement.

15. In a machine for wrapping bundles of

compressible material, said machine provided with a traveling carrier for the bundle to be wrapped and the wrapper thereof, means for compressing the bundle to a lesser height than that which it tends normally to assume, means for wrapping and securing the wrapper loosely about the bundle while under compression thereby to hold the bundle in a firm package when released from said compressing means. 75

16. In a machine for wrapping bundles of compressible material, said machine provided with a traveling carrier for the bundle to be wrapped and the wrapper thereof, means for compressing the bundle to a lesser height than that which it tends normally to assume, means for wrapping a band-like wrapper loosely about the bundle while still under such compression, thereby to hold the bundle in a firm package when released from said compressing means, means for pasting the ends of the wrapper together while still under said compression, and means for effecting the drying of the pasted seam of the wrapper before the bundle is released from said compression. 90

17. In a machine for wrapping bundles of compressible material, a main frame, a traveling carrier mounted therein adapted to carry a wrapping sheet supporting a bundle, a supplemental frame mounted vertically adjustable on said main frame and means carried by said supplemental frame for compressing said bundle to a lesser height than that which it tends normally to assume. 95

18. In a bundle wrapping machine, a main frame, a traveling carrier mounted therein adapted to carry a wrapping sheet supporting a bundle, a supplemental frame mounted vertically adjustable on said main frame and pivotal about its forward end and means carried by said supplemental frame for compressing said bundle to a predetermined height. 100

19. In a machine for wrapping bundles of compressible material, a traveling carrier adapted to carry a wrapping sheet supporting a bundle, means co-operating with said carrier for compressing said bundle to a predetermined height, such means comprising an endless belt running in the same direction as said carrier, said belt arranged to apply gradually increased pressure to the bundle passing thereunder. 110

20. In a machine for wrapping bundles of compressible material, a traveling carrier adapted to carry a wrapping sheet supporting a bundle, means co-operating with said carrier for compressing said bundle to a predetermined height, such means comprising an endless belt running in the same direction as said carrier, the forward end of said belt being spaced above the carrier relatively to the height to which said bundle shall be compressed and the rear end of said belt being spaced a greater distance from said carrier. 125

21. In a machine for wrapping bundles of compressible material, a main frame, a traveling carrier mounted therein adapted to carry a wrapping sheet supporting a bundle, means co-operating with said carrier for compressing in height the bundle carried on the latter, such means consisting of a supplemental frame mounted in said main frame and pivotal about its forward end, pulleys, carried by the opposite ends of said supplemental frame, a belt running on said pulleys in the same direction as the carrier and the forward end of said frame being located spaced above the carrier relatively to the predetermined height to which the bundle carried by said carrier shall be compressed.
22. In a machine for wrapping bundles of compressible material, a main frame, a traveling carrier mounted therein adapted to carry a wrapping sheet supporting a bundle, means co-operating with said carrier for compressing in height the bundle carried on the latter, such means consisting of a supplemental frame mounted vertically adjustable in said main frame and pivotal about its forward end, pulleys, carried by the opposite ends of said supplemental frame, a belt running on said pulleys in the same direction as the carrier, said forward end of said frame being located spaced above the carrier relatively to the predetermined height to which the bundle carried by said carrier shall be compressed.
23. In a machine for wrapping bundles of compressible material, a frame comprising upper and lower parallel sections, the upper thereof being vertically adjustable relatively to the lower, a traveling carrier mounted in said lower frame-section adapted to carry a wrapping sheet supporting a bundle, a bridge section carried by said upper frame section located in the middle of the machine, above and parallel with said carrier, and spaced from the latter relatively a predetermined height of the bundle carried thereby, means mounted in said upper frame section for compressing the bundle carried by said carrier to the height permitting the bundle to pass under said bridge section, means functioning during the forward movement of the carrier to lift the lateral ends of the wrapping sheet carried by the carrier against the sides of the bundle carried by the latter, and means functioning during the forward movement of the carrier to fold the extremities of said lateral ends, one over the other, over said bridge section, the latter means being carried by said upper frame-section.
24. In a machine for wrapping bundles of compressible material, a frame comprising upper and lower parallel sections, the upper thereof being vertically adjustable relatively to the lower, a traveling carrier mounted in said lower frame-section adapted to carry a wrapping sheet supporting a bundle, a bridge section carried by said upper frame section located in the middle of the machine, above and parallel with said carrier, and spaced from the latter relatively a predetermined height of the bundle carried thereby, means mounted in said upper frame section for compressing the bundle carried by said carrier to the height permitting the bundle to pass under said bridge section, means functioning during the forward movement of the carrier to lift the lateral ends of the wrapping sheet carried by the carrier against the sides of the bundle carried by the latter, and means functioning during the forward movement of the carrier to fold the extremities of said lateral ends, one over the other, over said bridge section, the latter means being carried by said upper frame-section.
25. In a bundle wrapping machine, a traveling carrier adapted to carry a wrapping sheet supporting the bundle, means for compressing the bundle to a predetermined height, comprising pulleys, in part driven, journaled above said carrier, and a belt running on said pulleys, such belt composed of a plurality of spaced members, a bridge located above said carrier and adjacent the forward end of said compressing means, and in a plane to permit the compressed bundle to pass under it, said bridge being provided with slots in which said belt members travel.
26. In a bundle wrapping machine, a traveling carrier adapted to carry a wrapping sheet supporting the bundle, means for compressing the bundle to a predetermined height comprising pulleys, in part driven, journaled above said carrier, and a belt running on said pulleys, such belt composed of a plurality of spaced members, a bridge located above said carrier and adjacent the forward end of said compressing means, and in a plane to permit the compressed bundle to pass under it, said bridge being provided with slots in which said belt members travel, means co-operating with said carrier, located adjacent to and forward of said bridge and adapted to hold said bundle compressed as received and while moved forward from said bridge.
27. In a bundle wrapping machine, a traveling carrier adapted to carry a wrapping sheet supporting the bundle, means for compressing the bundle to a predetermined height comprising pulleys, in part driven, journaled above said carrier, and a belt running on said pulleys, such belt composed of a plurality of spaced members, a bridge located above said carrier and adjacent the forward end of said compressing means, and in a plane to permit the compressed bundle to pass under it, said bridge being provided with slots in which said belt members travel.

- bridge being provided with slots in which said belt members travel, and a traveling belt located at the far end of said carrier above and parallel with the latter, adapted to bear 5 on the top of the bundle carried by the carrier as received from said bridge, co-operating with said carrier in effecting the further movement of the bundle through the machine and holding the bundle in its said compressed 10 state during such further movement.
28. In a machine for wrapping bundles of compressible material, a main frame comprising upper and lower sections, a series of horizontally disposed rollers mounted transversely in the lower section of said main frame and 15 extending substantially the whole length thereof, an endless belt-like carrier whose upper course is supported by said rollers, and which is adapted to carry a wrapping sheet 20 supporting a bundle, a bridge section located in the middle of the machine above and parallel with said carrier, and spaced from the latter relatively to a predetermined height of the bundle carried thereby, means for compressing the bundle carried by said carrier to the height permitting the bundles to pass under said bridge section, and means in co-operation 25 with said carrier functioning first to lift the lateral ends of the wrapping sheet against the sides of the bundle and then to fold the extremities of said ends one over the other, over 30 said bridge section.
29. In a machine for wrapping bundles of compressible material, a main frame comprising upper and lower sections, a series of horizontally disposed rollers mounted transversely in the lower section of said main frame and 35 extending substantially the whole length thereof, an endless belt-like carrier whose upper course is supported by said rollers, and which is adapted to carry a wrapping sheet 40 supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass 45 under said bridge section.
30. In a machine for wrapping bundles of compressible material, a main frame comprising upper and lower sections, a series of horizontally disposed rollers mounted transversely in the lower section of said main frame and 50 extending substantially the whole length thereof, an endless belt-like carrier whose upper course is supported by said rollers, and which is adapted to carry a wrapping sheet 55 supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass 60 under said bridge section.
31. In a machine for wrapping bundles of compressible material, a main frame comprising upper and lower sections, a series of horizontally disposed rollers mounted transversely in the lower section of said main frame and 65 extending substantially the whole length thereof, an endless belt-like carrier whose upper course is supported by said rollers, and which is adapted to carry a wrapping sheet 70 supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass 75 under said bridge section, and means in co-operation with said carrier functioning first to lift the lateral ends of the wrapping sheet against the sides of the bundle and then to fold the extremities of said ends one over the other, over 80 said bridge section.
32. In a machine for wrapping bundles of compressible material, a main frame comprising upper and lower sections, a series of horizontally disposed rollers mounted transversely in the lower section of said main frame and 85 extending substantially the whole length thereof, an endless belt-like carrier whose upper course is supported by said rollers, and which is adapted to carry a wrapping sheet 90 supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass 95 under said bridge section, and means in co-operation with said carrier functioning first to lift the lateral ends of the wrapping sheet against the sides of the bundle and then to fold the extremities of said ends one over the other, over 100 said bridge section, and means co-operating with said carrier and located adjacent to and forward of said bridge section, adapted to hold said bundle compressed as received and while moved from said bridge section through the far end of the machine.
33. In a machine for wrapping bundles of compressible material, a main frame comprising upper and lower sections, a series of horizontally disposed rollers mounted transversely in the lower section of said main frame and 105 extending substantially the whole length thereof, an endless belt-like carrier whose upper course is supported by said rollers, and which is adapted to carry a wrapping sheet 110 supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass 115 under said bridge section, and means in co-operation with said carrier functioning first to lift the lateral ends of the wrapping sheet 120 against the sides of the bundle and then to fold the extremities of said ends one over the other, over said bridge section, a series of belt carriers journaled transversely in said upper frame-section in the far end of the machine and above said carrier, and a driven belt 125 running over said belt carriers with its lower course bearing against the under sides of said belt carriers, said lower course being arranged to be approximately in the same plane as the underside of said bridge section, thereby per- 130

mitting the bundle as carried forward from the latter to pass under said belt, and hold the bundle in its compressed state while passing through the far end of the machine.

- 5 33. In a machine for wrapping bundles of compressible material, a main frame comprising upper and lower sections, a series of horizontally disposed rollers mounted transversely in the lower section of said main frame and extending substantially the whole length thereof, an endless belt-like carrier whose upper course is supported by said rollers, and which is adapted to carry a wrapping sheet supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass under said bridge section, and means co-operating with said carrier and located adjacent to and forward of said bridge section, adapted to hold said bundle compressed as received and while moved from said bridge section through the far end of the machine.
- 10 34. In a machine for wrapping bundles of compressible material, a main frame comprising upper and lower sections, a series of horizontally disposed rollers mounted transversely in the lower section of said main frame and extending substantially the whole length thereof, an endless belt-like carrier whose upper course is supported by said rollers, and which is adapted to carry a wrapping sheet supporting a bundle, a bridge section located in the middle of the machine above and parallel with said carrier, and spaced from the latter relatively to a predetermined height of the bundle carried thereby, means for compressing the bundle carried by said carrier to the height permitting the bundle to pass under said bridge section, a series of belt carriers journaled transversely in said upper frame-section in the far end of the machine and above said carrier, and a driven belt running over said belt carriers with its lower course bearing against the under sides of said belt carriers, said lower course being arranged to be approximately in the same plane as the under side of said bridge section, thereby permitting the bundle as carried forward from the latter to pass under said belt, to be held holding the bundle in its compressed state while passing through the far end of the machine.

- 15 35. In a machine for wrapping bundles of compressible material, a main frame comprising upper and lower sections, the upper section being vertically adjustable relatively to the lower, a series of horizontally disposed rollers mounted transversely in the lower section of said main frame and extending substantially the whole length thereof, an endless belt-like carrier whose upper course is sup-

ported by said rollers, and which is adapted to carry a wrapping sheet supporting a bundle, a bridge section carried by said upper frame section located in the middle of the machine above and parallel with said carrier, and spaced from the belt carrier relatively to a predetermined height of the bundle carried thereby, means carried by said upper frame section for compressing the bundle carried by said carrier to the height, permitting the bundles to pass under said bridge section means in co-operation with said carrier functioning first to lift the lateral ends of the wrapping sheet against the sides of the bundle and then to fold the extremities of said ends one over the other, over said bridge section, means carried by said upper frame-section co-operating with said carrier and located adjacent to and forward of said bridge section, adapted to hold said bundle compressed as received and while moved from said bridge section through the far end of the machine.

20 36. In a machine for wrapping bundles of compressible material, a main frame comprising upper and lower sections, the upper section being vertically adjustable relatively to the lower, a series of horizontally disposed rollers mounted transversely in the lower section of said main frame and extending substantially the whole length thereof, an endless belt-like carrier whose upper course is supported by said rollers, and which is adapted to carrying a wrapping sheet supporting a bundle, a bridge section carried by said upper frame section located in the middle of the machine above and parallel with said carrier, and spaced from the latter relatively to a predetermined height of the bundle carried thereby, means carried by said upper frame section for compressing the bundle carried by said carrier to the height permitting the bundle to pass under said bridge section, means in co-operation with said carrier functioning first to lift the lateral ends of the wrapping sheet against the sides of the bundle and then to fold the extremities of said ends one over the other, over said bridge section, a series of belt carriers journaled transversely in said upper frame section in the far end of the machine above said carrier, and a driven belt running over said belt carriers with its lower course bearing against the under sides of said belt carriers, said lower course being arranged to be approximately in the same plane as the under side of said bridge section, thereby permitting the bundle as carried forward from said bridge section to pass under said belt, and holding the bundle in its compressed state while passing through the far end of the machine.

25 37. In a machine for wrapping bundles of compressible material, a main frame comprising upper and lower sections, the upper section being vertically adjustable relatively to

the lower, a series of horizontally disposed rollers mounted transversely in the lower section of said main frame and extending substantially the whole length thereof, an endless belt-like carrier whose upper course is supported by said rollers, and which is adapted to carry a wrapping sheet supporting a bundle, a bridge section carried by said upper frame section located in the middle of the machine above and parallel with said carrier, and spaced from the latter relatively to a predetermined height of the bundle carried thereby, means carried by said upper frame section for compressing the bundle carried by said carrier to the height permitting the bundles to pass under said bridge section, means in co-operation with said carrier functioning first to lift the lateral ends of the wrapping sheet against the sides of the bundle and then to fold the extremities of said ends one over the other, over said bridge section.

38. In a machine for wrapping bundles of compressible material, a main frame comprising upper and lower sections, the upper section being vertically adjustable relatively to the lower, a series of horizontally disposed rollers mounted transversely in the lower section of said main frame and extending substantially the whole length thereof, an endless belt-like carrier whose upper course is supported by said rollers, and which is adapted to carry a wrapping sheet supporting a bundle, a bridge section carried by said upper frame section located in the middle of the machine above and parallel with said carrier, and spaced from the latter relatively to a predetermined height of the bundle carried thereby, means carried by said upper frame section for compressing the bundle carried by said carrier to the height permitting the bundle to pass under said bridge section.

39. In a bundle wrapping machine in combination with a continuous carrier for carrying a wrapping sheet supporting a bundle, means for delivering a wrapping sheet to said carrier, means for creasing said delivered sheet longitudinally, such means comprising four creasers arranged side by side, two of said creasers being arranged to make creases in the wrapping sheet along the sides of the bottom of the bundle and the other two creasers being arranged to make creases in the wrapping sheet spaced from said bottom creasers relatively to the top of the bundle, the creasers for making said bottom crease on one side of the bundle and the other two creasers for making said top creases on both sides of the bundle being movable, means for automatically moving the top creasers adjacent said movable creaser in unison with the latter.

40. In a bundle wrapping machine in combination with a continuous carrier for carrying a wrapping sheet supporting a bundle, means

for delivering a wrapping sheet to said carrier, means for creasing said delivered sheet longitudinally, such means comprising four creasers arranged side by side, two of said creasers being arranged to make creases in the wrapping sheet along the sides of the bottom of the bundle and the other two creasers being arranged to make creases in the wrapping sheet spaced from said bottom creasers relatively to the top of the bundle, the creaser for making said bottom crease on one side of the bundle and the creasers for making said top creases on both sides of the bundle being movable, and means for automatically moving said movable creasers relatively to each other. 80

41. In a bundle wrapping machine, in combination with a continuous carrier adapted for carrying a wrapping sheet supporting a bundle, means for delivering a wrapping sheet to said carrier, means for creasing said delivered sheet longitudinally, said creasing mechanism comprising a plurality of creaser units arranged side by side, and adjustable relatively to each other, connections between said creasers by which they may be set in unison and the relative positions of each thereof is maintained during each setting. 85

42. In a bundle wrapping machine, in combination with a continuous carrier adapted for carrying a wrapping sheet supporting a bundle, means for delivering a wrapping sheet to said carrier, means for creasing said delivered sheet longitudinally, said creasing mechanism comprising a plurality of creaser units arranged side by side, and adjustable relatively to each other, devices for folding the lateral ends of said sheet about the bundle carried by said carrier, the latter devices also being adjustable, and connections between said folding devices and said creasers by which they may be set in unison and the relative positions of each thereof is maintained during such setting. 105

43. In a bundle wrapping machine, in combination with a continuous carrier adapted for carrying a wrapping sheet supporting a bundle, means for delivering a wrapping sheet to said carrier, means for creasing said delivered sheet longitudinally, means for cutting said delivered sheet into pieces of desired length, said creasing mechanism comprising a plurality of creaser-units arranged side by side, and adjustable relatively to each other, devices for folding the lateral ends of said sheet about the bundle carried by said carrier, the latter devices also being adjustable, and connections between said folding devices and said creasers by which they may be set in unison and the relative positions of each thereof is maintained during such setting. 110

44. In a machine for wrapping bundles of compressible material, a travelling carrier adapted to support a wrapping sheet supporting a bundle, and means cooperating with 130

the carrier adapted to compress the bundle to a lesser than its normal height, and means for wrapping the wrapping sheet about the bundle with the wrapping sheet arranged to 5 correspond with the cross-section the bundle shall be permitted to assume when released.

45. In a machine for wrapping bundles of compressible material, a travelling carrier adapted to support a wrapping sheet supporting a bundle, and means cooperating with the carrier adapted to compress the bundle to a lesser than its normal height, means for wrapping the wrapping sheet about the bundle with the wrapping sheet arranged to 10 correspond with the cross-section the bundle shall be permitted to assume when released, and in combination with means for applying adhesive to one end of the wrapping sheet, and means for thereupon heating said end 15 and holding the bundle under compression for 20 a period.

46. A machine for wrapping compressible bundles comprising a travelling carrier adapted to carry a wrapping sheet supporting a bundle, adjustable means for applying adhesive to one end of the wrapping sheet, adjustable means for compressing the bundle carried by said carrier, adjustable means for 25 folding the wrapping sheet about the bundle 30 while under compression, and means whereby to adjust all of said means in unison for operating on bundles of different sizes.

47. In a machine for wrapping bundles of compressible material, said machine comprising a lower frame section, an adjustable upper frame section extending substantially horizontally, and vertically movable, and a travelling carrier supported by the said lower frame section, said lower frame section provided 35 with adjustable creasing means, adjustable means for applying adhesive to one end of the wrapping sheet, adjustable means for compressing the bundle carried by said carrier, 40

adjustable means for folding the wrapping sheet about the bundle while under compression, and means whereby to adjust all of said means in unison for operating on bundles of different sizes.

48. In a machine for wrapping bundles of compressible material, said machine comprising a lower frame-section, an adjustable upper frame section extending substantially horizontally, and vertically movable, and a travelling carrier supported by the said lower frame section, adjustable means for applying adhesive to one end of the wrapping sheet, adjustable means for compressing the bundle carried by said carrier, adjustable means for folding the wrapping sheet about the bundle while under compression, and means to adjust said upper frame-section relatively to the lower frame-section and in unison therewith all said other means, whereby to arrange the machine to operate on bundles of different sizes.

49. In a machine for wrapping bundles of compressible material, said machine comprising a lower frame-section, an adjustable upper frame-section extending substantially horizontally, and vertically movable, and a travelling carrier supported by the said lower frame-section, said lower frame-section provided with adjustable creasing means, adjustable means for applying adhesive to one end of the wrapping sheet, adjustable means for compressing the bundle carried by said carrier, adjustable means for folding the wrapping sheet about the bundle while under compression, and means to adjust said upper frame-section relatively to the lower frame-section and in unison therewith all said other means, whereby to arrange the machine to operate on bundles of different sizes.
